UNITED STATES PATENT OFFICE

JOHN B. JOHNSON, OF ELMHURST, NEW YORK, ASSIGNOR TO WESTERN ELECTRIC COMPANY, INCORPORATED, OF NEW YORK, N. Y., A CORPORATION OF NEW YORK

ELECTRON-DISCHARGE DEVICE

Application filed July 2, 1925. Serial No. 41,051.

This invention relates to electron discharge devices and circuits employing the same, and particularly electron discharge devices employing thermionic cathodes and circuit arrangements for heating the cathodes with fluctuating current.

One of the objects of the invention is to improve the action of an electron discharge devise:

10 A further object of the invention is to prevent disturbances in the output of an electron discharge device due to variations in the cathode heating current.

It is often desirable to heat the cathode of 15 electron discharge devices by means of current from an alternating or varying source of potential. When this is done, however, the potential between the cathode and control electrode and between the cathode and 20 anode varies in accordance with the voltage impressed on the cathode, thus producing fluctuations in the output current of the device.

In accordance with this invention, the cathode, control electrode and anode are arranged 25 in parallel relationship within an enclosing vessel and taps brought out from both ends of each electrode, so that a voltage equal to that impressed on the cathode for heating 30 may be impressed on both the control electrode and the anode. Adjacent points on the three electrodes are thereby maintained at the same potential irrespective of variations in the cathode heating current and no changes 35 will be produced in the space current thereby.

When the cathode of an electron discharge device is heated by means of an electric current flowing therethrough the two terminals of the cathode will be at different potentials 40 due to the RF drop. When the ordinary type of anode is employed and this anode maintained at a definite potential with respect to the cathode by means of an external source, the anode-cathode potential will vary at different points along the cathode. As is well 45 recognized in the art the output of an electron discharge device is within certain limits dependent upon the anode-cathode potential. Therefore, if the external source is adjusted 50 to such a value as to give maximum efficiency

of operation, other points on the cathode will be operating at inefficient potentials and the entire area of the cathode will not be used to the greatest advantage. The deleterious results of this effect will be most pronounced 55 in devices provided with cathodes of considerable length where a large cathode area is desirable for giving a high energy output.

The arrangement of this invention above described in which the three electrodes are 60 arranged parallel and the same longitudinal potential impressed thereon to maintain adjacent points at the same potential makes it possible to maintain all points on the cathode at the optimum potential with respect to the 65 anode, so that the entire surface of the cathode is utilized to the best advantage.

This invention can be readily understood by reference to the following description in connection with the drawing which shows diagrammatically one embodiment.

A three-electrode vacuum tube, 3, having a filamentary cathode 4, a control electrode or grid 5 and an anode 6 arranged according to this invention is shown in an amplifier circuit 75 equipped with means for heating the cathode with alternating current, the electrodes are merely shown diagrammatically as any particular form is not material to the invention. The grid and anode are arranged parallel to one another and to the cathode and each is provided with terminals at both ends. While it is preferable to make the electrodes 80 of parallel wires arranged non-inductively so as not to introduce any magnetic fields which would affect the electron stream, the grid and anode may readily be constructed of parallel plane, cylindrical or other suitable shape. The grid and anode must be of comparatively high resistance so as not to be heated 85 when a voltage equal to the cathode voltage is impressed along them, while the cathode is made in the usual manner so that it is heated to incandescence to give off electrons.

Filament heating current is supplied from 90 an alternating current source 7, through a transformer 8 which is provided with a primary winding 9 connected to the source 7 through a rheostat 10. A secondary winding 11 of the transformer is connected to the 100

cathode 4 for supplying current thereto. Two other secondary windings 12 and 13 are also provided for applying equal voltages across the grid 5 and the anode 6. These 5 windings each have the same number of turns and are wound in the same direction as the winding 11, so that equal voltages of the same phase are impressed on the electrodes to maintain adjacent points on all three at the same potential. By connecting the rheostat 10 in 10 the primary circuit the filament current can be controlled without affecting the equality of the electrode voltages.

The tube is associated with the other apparatus 15 in the amplifier circuit in the usual manner, the connections to the electrodes preferably being made at the electrical centers of their respective transformer windings so as to keep the inductive coupling between 20 the input and output circuits at a minimum. Thus the secondary winding of the input transformer 14 is connected in series with the grid biasing battery 15 to the mid-points of 25 the grid winding 12 and the cathode winding 11 while the receiver 16, representing the output circuit, is connected in series with the plate battery 17 to the mid-points of the 30 anode winding 13 and the cathode winding 11. If it is desired, the mid-point of the cathode winding may be grounded by means of a connection 18.

The invention has been described with respect to an audio frequency amplifier circuit but may obviously be applied to other circuits 35 such as detectors, high frequency amplifiers or even oscillators if desired.

What is claimed is:

1. An electron discharge device comprising 40 a thermionic cathode, a control element and an anode arranged in parallel space relationship, means for supplying alternating heating current to said cathode, and means for applying along said anode a voltage equal to the IR drop along said cathode to maintain 45 adjacent points on said two electrodes at the same potential.

2. An electron discharge device comprising 50 a thermionic cathode, a control electrode, an anode and means for impressing the same alternating voltage on the three electrodes to maintain adjacent points on said electrodes at substantially the same potential.

3. An electron discharge device comprising 55 a thermionic cathode, a control electrode, an anode, means for impressing a fluctuating potential on said cathode for supplying heating current thereto, and means for impressing an equal fluctuating potential from the same source on said control electrode to prevent fluctuations in said heating current from 60 producing disturbances in the space current of said device.

4. An electron discharge device comprising 65 a thermionic cathode, a control electrode, and an anode arranged in parallel space relation-

ship, means for supplying fluctuating current for heating said cathode, and means for impressing current from the same source on said control electrode and anode to always maintain adjacent points on said three electrodes at the same potential with regard to the cathode heating current. 70

5. An electron discharge device comprising 75 an enclosing vessel containing a thermionic cathode, a control electrode, and an anode arranged in parallel space relationship, means for impressing alternating current on said cathode for heating the same and means for impressing alternating current of the same potential and phase on said control 80 electrode and anode to maintain adjacent points on said three electrodes at the same potential.

6. In combination, an electron discharge 85 device having a thermionic cathode, a control electrode and an anode arranged in parallel space relationship and each provided with terminals at both ends, a source of alternating current and a transformer having a primary winding connected to said source, a secondary winding connected to the terminals of 90 said cathode for supplying heating current and two other secondary windings having the same number of turns as said first secondary winding connected to said control electrode and anode, respectively, for impressing thereon a potential of the same phase and equal to the potential impressed on the cathode to maintain adjacent points on said three electrodes at the same potential with regard to the 95 cathode heating current. 100

7. An electron discharge device comprising 105 a filamentary cathode, a control electrode, an anode, said control electrode and anode being arranged parallel to one another and to said cathode and being of comparatively high resistance so as not to be heated to incandescence when a voltage equal to the cathode voltage is impressed thereon, means for supplying an alternating current to said cathode for heating and means for impressing an alternating current of the same phase and voltage on said control electrode and anode to maintain adjacent points on said three electrodes at the same potential. 110

8. An electron discharge device comprising 115 a thermionic cathode, a control electrode, an anode, a source of alternating current, and means for heating the cathode by said alternating current and for impressing alternating current from said source in the same phase relation on the control element and the anode. 120

In witness whereof, I hereunto subscribe my name this 26 day of June A. D. 1925.

JOHN B. JOHNSON.
